UNITED STATES PATENT OFFICE.

SAMUEL E. AUTREY AND JOSEPH M. MITCHELL, OF SHERMAN, TEXAS.

GAS GENERATOR AND BURNER.

1,175,218.

Specification of Letters Patent. Patented Mar. 14, 1916.

Application filed July 26, 1915. Serial No. 42,001.

To all whom it may concern:

Be it known that we, SAMUEL E. AUTREY and JOSEPH M. MITCHELL, citizens of the United States, residing at Sherman, in the county of Grayson and State of Texas, have invented certain new and useful Improvements in Gas Generators and Burners, of which the following is a specification.

This invention relates to a combined gas generator and burner for kerosene oil, and it particularly relates to a device of this character adapted to be employed in connection with ordinary cooking and heating stoves, furnaces, and the like, or for divers other purposes.

An object of the invention is to provide a device of this character which may be fitted into the fire-box and seated upon the grate of stoves of different sizes, and which shall be comparatively simple, durable, and inexpensive in its construction, as well as being practical and efficient in operation.

A further object of the invention is to provide a burner embodying a retort in connection with a superheating pipe, whereby the retort, in being heated, will vaporize or gasify the liquid fuel in order that the gas or vapor may be heated to a high temperature in the superheater pipe, and a most effective combustion of gas result to produce a maximum heating effect with a minimum expenditure of fuel.

This invention also embodies various subordinate features of construction and combinations of parts, all subservient to the broad features above outlined, which will be more fully described hereinafter, illustrated in the accompanying drawings, and finally pointed out in the claim hereunto appended, it being understood that changes in the precise embodiment of the invention herein disclosed can be made within the scope of what is claimed without departing from the spirit of the invention.

The invention has been illustrated in its preferred form in the accompanying drawings, wherein:—

Figure 1 represents a front elevation of a stove with the burner applied, portions being broken away. Fig. 2 is a plan view of the same; and Fig. 3 is an enlarged detail view of one of the retorts removed.

Referring more particularly to the drawings in which similar reference numerals designate corresponding parts throughout

the several views, 1 indicates a stove of ordinary construction and 2 the usual grate bars thereof. A suitable rectangular base 3 is seated upon the grate bars and extends longitudinally nearly the length of the fire-box 4. A pair of cylindrical retorts, 5 and 6, are seated upon the base, one near each end thereof, and centrally located and secured to the bottom of the retorts are tubes 7 and 8 that extend upwardly within them for about two-thirds their height, and downwardly through their bottom ends, also through apertures in the base 3, where elbows 9 and 10 are attached thereto; the downward projecting ends of the tubes being of the proper length to permit the connected ends of the elbows to rest adjacent to the under side of the base 3, and thus serve to retain the retorts securely in position upon the base. To the other ends of the elbows 9 and 10 are connected oil supply pipes 11 and 12, that are disposed horizontally beneath the base, to and through an opening in the door at the opposite end of the stove, whence they branch laterally as shown at 13 and 14, and are fitted with the usual angle oil supply valves 15 and 16, which valves are in turn connected with the top side of a laterally disposed oil receiver 17, through vertical check valves 18 and 19.

The retorts 5 and 6 are filled with small pebbles or analogous slightly absorbent material nearly to the top of their upstanding inner tubes, and attached to the top ends of the retorts are elbows 20 and 21, each fitted with a pipe comprising a superheating and burner section, the former consisting of horizontal portions 22 and 23, bent over and downward so as to constitute burner pipe sections 24 and 25, that are closed at the ends and provided with jet openings, as indicated at 26 and 27. Secured to the superheating sections, by any proper means such as, for instance, set screws as shown, are deflectors or spreaders 28 and 29, centrally located over the gas jets and adapted to spread the flame when the gas from said jets is burning. Small brass wires 30 are disposed within the superheating pipes to assist in heating the vapor or gas passing therethrough, and they also tend, together with the pebbles in the retorts, to collect all carbonaceous matter, should any be formed in the process of converting the liquid fuel into gas.

31 and 32 represent priming pans bridg-

ing openings 33 and 34 extending through the base 3, beneath the jets 26 and 27; said pans may have a layer of asbestos therein to absorb the oil primarily required to start 5 the burners,—the oil being ignited therefrom. A fuel supply tank 35 may be supported in any convenient manner above the level of the burners and connected with the bottom side of the reservoir 17, by a pipe 36. 10 In operation, liquid fuel, such as coal oil, or the like may be fed by gravity or under pressure, from the supply tank, through the supply pipe, and check valves, where the quantity thereof is regulated by the valves 15 and 16, and the oil continues its course thence and flows through the pipes 11 and 12, and initially, to the retorts 5 and 6, through the superheating and burner sections, and out through the jets 26 and 27, 15 and partly fills the priming pans 31 and 32, whereupon the supply is cut off by means of the valves and the fuel within the pans ignited, thereby heating the retorts and pipe sections to such an extent that if the oil 20 is again admitted the heat upon the retorts and sections quickly converts the oil therein into gas, and the burning of the gas from the jets keeps the retorts and pipe sections continually hot enough to continue the generation of gas so long as fuel is admitted 25 through the pipes. When the primary charging supply of oil is consumed, oil will 30 thereafter only slowly ooze from the tubes 7 and 8, to the pebbles contained in the retorts, which being very hot, vaporizes the oil, whence it passes to the superheating sections and is thoroughly gasified before reaching the burner jets; and a slight variation from a predetermined pressure of the gas will then either slightly open or close 35 the check valves 18 and 19 and automatically regulate the oil supply, even if the valves 15 and 16 are fully opened.

Having thus described our invention, what we claim as new, and desire to secure 45 by Letters Patent of the United States, is—

In a gas generator and burner for stoves and the like, a base, a retort at each end of the base and supported thereby, absorbent material and an upstanding tube in each 50 retort, said tubes connected through the bottom ends of the retorts to liquid fuel supply pipes, a pipe connected with the top of each retort that comprises superheating and burner sections, the latter having a jet opening therein, and means for supplying liquid fuel to the fuel supply pipes, as set forth. 55

In testimony whereof we affix our signatures in presence of two witnesses.

SAMUEL E. AUTREY.
JOSEPH M. MITCHELL.
